UNITED STATES PATENT OFFICE

2,554,338

WATER HEATER

Morris Levine, New York, N. Y.

Application May 17, 1947, Serial No. 748,821

1 Claim. (Cl. 122—20)

1

This invention relates to means for heating water for kitchen use as well as for room heating purposes.

The principal object of this invention is the provision of heating means of the character described which may be used in conventional coal and oil burning furnaces. It comprises an attachment which may be mounted inside of the furnace and which may be connected to the water jacket thereof. It is also connected to the hot water tank of the system in addition to the connections which are conventionally provided between the water jacket of the furnace and the hot water tank. The water heating means under discussion is really auxiliary to the conventional water heating means with which furnaces are provided, but the heating capacity of this auxiliary means may exceed the heating capacity of the conventional water heating system.

Another object of this invention is the provision of a water heating tank which is positioned within conventional furnaces with its bottom at a level below the top level of the burning coal. When used in connection with oil burning furnaces, this water heating tank is situated so that the flames actually make contact with it.

Another object of this invention is the provision of a water heating means auxiliary to the water heating system of conventional furnaces, said auxiliary water heating means taking the form of a smoke pipe which connects the furnace to the chimney, said smoke pipe having a sinuous form and extending through the hot water tank of the system.

A further object of this invention is the provision of additional means for heating the water, said additional means comprising a compound pipe, that is one pipe within another, the inside pipe being the water pipe and the outside pipe being the smoke pipe whereby the hot gases that ordinarily escape through the chimney may be utilized to heat the water.

Preferred embodiments of this invention are shown on the accompanying drawing in which:

Fig. 1 is a side view of a conventional coal burning furnace and a conventional hot water tank incorporating the features of the present invention, said furnace being partly broken away to expose, in vertical section, one of the auxiliary heating elements, and the tank being shown also in vertical section to expose the smoke pipe extending therethrough, said smoke pipe being itself partly broken away to reveal the water pipe contained therein.

Fig. 2 is a perspective view of the auxiliary

2

heating element shown in Fig. 1 which is mounted within the coal burning furnace; and

Fig. 3 is a perspective view of a second form of this invention.

Referring to Fig. 1 it will be seen that a conventional coal burning furnace 10 is provided with a water jacket 11 communicating through pipes 12 and 13 with a hot water tank 14. The pipe 12 leads water from the furnace to the tank 14. The water in the tank 14 can be recirculated by means of the pipe 13 (see upper left hand corner of Fig. 1) which leads back to the water jacket 11. Thus far a conventional installation has been described. It will be noted that two auxiliary hot water tanks 20 and 21, respectively, are mounted in the combustion chamber of furnace 10 and that their lower ends extend into the burning coal 23. They are supported in the furnace by means of brackets 24 and 25, respectively. Pipes 27 and 28 provide communication between these two tanks, and pipes 29 and 30 provide communication between tank 20 and the water jacket 11 of the furnace. Another pipe 32 provides communication between tank 20 and conventional hot water tank 14 above mentioned.

It will be noted that a smoke pipe or flue 40 carries off the hot gases from the combustion chamber of furnace 10 and directs them into the chimney (not shown). This pipe 40 is provided with several bends or curves which gives it a sinuous form. These bends are formed in the pipe outside of tank 14 as well as inside of the tank. It will be noted that the bends inside of tank 14 are directed from side to side and not upwardly and downwardly. The bends inside of the tank are more clearly shown in Fig. 3. The essential difference between the bends in Fig. 1 and those shown in Fig. 3 is the fact that the bends in Fig. 1 all lie on a common horizontal plane inside of the tank whereas the bends in Fig. 3 slope upwardly. Actually the bends in Fig. 3 extend from side to side but always on a sloping plane which extends upwardly from the inlet end of the tank to the outlet end. On the other hand, the bends outside of tank 14 extend both vertically and horizontally. In no case, however, do the bends outside of tank 14 slope downwardly as viewed from the inlet end to the outlet end of the bends outside of the tank. The principle underlying the fact that none of the bends carry the pipe downwardly as viewed from the inlet end to the outlet end of the pipes in question, is the requirement that at all times the smoke be made to travel upwardly or at least on a horizontal line but certainly not downwardly.

It will be seen that pipe 32 which provides communication between tanks 20 and 14 extends through smoke pipe 40. It is apparent that bends corresponding to the bends in pipe 40 are formed in pipe 32.

From the foregoing it will be understood that when the furnace 10 is in operation, the tanks 20 and 21 will be exposed to the direct heat of the burning coal. The water in these tanks will very quickly be heated to a high temperature and the heated water will tend to flow upwardly through pipe 32 and into tank 14. The return flow will pass through pipe 12 into the water jacket 11 of the furnace and thence through pipe 30 into tanks 20 and 21. To a limited extent the circulatory system thus described will be short circuited by a return flow of the water in tanks 20 and 21 to the water jacket 11 through pipe 29. The bends in smoke pipe 40 will cause the hot combustion gases to enter into intimate contact with the pipe 32 which extends through said pipe 40. These gases will contribute to the process of heating the water in pipe 32. The bends or curves in pipe 40 which are formed inside of tank 14 provide a greater surface area of contact between said pipe and the water in tank 14 thereby giving the hot combustion gases in said pipe a greater opportunity to yield their heat through the pipe walls to the water in said tank 14.

The second embodiment of this invention is similar to the first embodiment in that a bent smoke pipe 50 extends through the water tank 51. It is also similar in that a hot water pipe 52 corresponding to the hot water pipe 32 extends through pipe 50 and leaves that pipe inside tank 51 adjacent the inlet end of said tank. Pipe 52 is therefore in direct communication between the water heater 55 and the inside of the water tank 51. The furnace 56 is also a conventional furnace, but its smoke outlet rises continuously in passing from the furnace to the hot water tank and extends in sinuous orientation generally horizontally thereof rather than generally vertically as is the case with the furnace shown in Fig. 1. Pipe 50, however, is provided with substantially the same number of bends as pipe 40 is shown in Fig. 1 to be provided. It will be noted that the bends in pipe 50 inside of tank 51 lie on a plane which slopes upwardly from the inlet end of the tank to the outlet end. In other words, a sectional view of tank 51 would appear similar to tank 14 in Fig. 1, except that sinuous pipe 50 would have its right end lower and its left end higher than pipe 40 in tank 14 of Fig. 1. Aside from this slope the bends in pipe 50 inside of water tank 51 extend from side to side rather than upwardly and downwardly.

Another difference between the embodiment under discussion and the first described embodiment resides in the means of fastening their respective water heaters to the inside of their respective furnaces, in Fig. 2 horizontally extending straps having vertically extending holes are fastened to the water heater. The way this is done is to mount the straps on brackets (not shown) which are attached to the inside of the furnace. In the present embodiment horizontally extending brackets 60 having horizontally extending holes are affixed to the water heater. Bolts extending through said holes fasten the water heater to the inside of the furnace.

What have above been described are preferred

embodiments of the instant invention, and it will be understood that modifications may be incorporated therein in accordance with the requirements of different types of furnace and for other purposes as well. For example, tanks 20 and 21 are given a unique shape rounded atop and bottom, somewhat larger at the top than at the bottom, the shape resembling somewhat an inverted raindrop. It may be found that only one tank rather than two will adequately serve the purpose intended, and it may also be found that tanks of different shape will be equally efficient. The number of bends in pipe 40 as it extends through tank 14 is not critical. A greater or lesser number of bends than shown may be used as and when desired.

The auxiliary heating means consisting of tanks 20 and 21, pipe 32 extending through bent smoke pipe 40 and the bent portion of pipe 40 which extends through tank 14, has above been described in connection with a hot water tank generally used to supply the household kitchen and bathroom with hot water. It will be appreciated that the same system may be used in connection with the steam heating system of the home or with its hot water heating system, wherever it may happen to be installed in a particular house. The hot water tank shown in the drawing is preferably lined with porcelain or a similar vitreous material but other types of hot water tank may also be used.

I claim:

In a furnace having a water jacket, a combustion chamber, and a separate hot water tank connected thereto, the combination of an auxiliary water tank mounted in the combustion chamber, a smoke stack from the furnace extending through the hot water tank, and a water pipe extending from the auxiliary tank in the furnace and disposed within and along said smoke stack and connected to the interior of the hot water tank, said smoke stack where it is outside of the hot water tank being sinuous in form and rising continuously in passing from the furnace to the hot water tank, and said water pipe within the smoke stack having its sinuous axis coincident throughout with that of the smoke stack.
